UNITED STATES PATENT OFFICE.

WALT C. MARSH, OF BELLEVILLE, ILLINOIS.

FOUNTAIN BRUSH.

Application filed May 17, 1923. Serial No. 639,479.

This invention relates to an improved fountain brush for use in stenciling or the like, and including a valve of improved construction and operation arranged in a novel relationship between the fountain and the brush so that the operator's forefinger will naturally and conveniently contact with the valve operating button to open the valve and to permit accurate control of the flow 10 of ink from the fountain to the brush.

The drawing Fig. 1 is a longitudinal sectional view of a fountain brush embodying my present invention.

Fig. 2 is a sectional view showing the 15 valve structure on an enlarged scale.

My invention is embodied in a fountain brush comprising a hollow handle 1 which constitutes the ink reservoir and which is screwed on the threaded end 2 of a body 20 member having a circumferential flange 3 serving as an abutment for the end of the handle reservoir. A hopper 4 is formed in the end 2 of the body member and opens into a tubular passage 5 extending entirely 25 through the body member. The lower end of the body member is provided with an enlargement 6 recessed in its lower side and provided with internal threads for receiving and supporting a ring 7 that binds the upper 30 ends of the brush bristles 8. A cavity 9 is formed in the lower end of the body above the ends of the bristles and receives the ink discharged from the passage 5. A nozzle 10 is secured centrally within the mass of 35 bristles forming the brush and conducts the ink from the cavity 9 to the brush bristles as will be readily understood by reference to the drawing. A pad 11 of felt or other appropriate material is clamped between the 40 ends of the bristles and the lower end of the supporting body and is provided with a central hole 12 permitting the ink to pass therethrough to the nozzle 10 for delivery to the brush bristles.

The supporting body is formed with a valve chamber 13 at right angles to and intersecting the passage 5. A valve plug 14 is operatively mounted within the valve chamber 13 and is provided with a stem 15 extending outwardly beyond the body member and having a finger button 16 secured to its outer end which is beyond the valve body and beyond the handle fountain 1 and in a position so that it will naturally and conveniently be engaged by the fore-finger 55 of the operator when the device is in use.

The body member is formed with a threaded hole in which a barrel 17 is screwed, the same having a nut 18 formed on its outer end for engagement by a wrench or the like in assembling and separating the parts. 60

The conical inner end 19 of the barrel 17 has a central hole through which the stem 15 of the valve extends and is filled with packing material 20 pressed to position by a ring 21 within the barrel. The ring is 65 held in place by a coil spring 22 of the expansion type encircling the valve stem 15 and having its inner end pressing against the ring 21 and its outer end pressing against the button member 16 within a cylindrical 70 bore. The button member 16 has a stem portion 23 extending into the barrel and guided thereby.

A circumferential groove 24 is formed in the valve 14 and, when the valve is pressed 75 inwardly by engagement of the finger of the operator with the valve operating button 16, said groove is brought into registration with the passage 5 to permit ink to flow through said passage to the brush. Obviously the 80 amount of ink flowing through the passage 5 to the brush may be optionally varied by operation of the valve. For instance, if a full flow of ink is desired the valve is pressed inwardly to place the groove 24 in full registration with the passage 5; whereas if a reduced amount of ink is desired the valve is operated only a sufficient distance to effect partial registration of the groove 24 with the passage 5. The valve is automatically closed when released as the power of the spring 21 is sufficient for that purpose. 90

The part 25 on the stem serves as an abutment to contact with the end of the barrel 17 and limit movement of the valve by the 95 spring 22. Said part 25 is of less diameter than the bore 13, so that the ink can freely pass from behind said part when the spring closes the valve.

The packing, which completely encircles 100 the valve stem, effectively prevents leakage of ink around the valve stem and thus avoids loss of ink and at the same time keeps the device clean.

From the foregoing it will be seen that my 105 invention is a highly efficient and simple one and completely obtains all of its intended objects and purposes. The construction of the parts may be varied without departure from the nature and principles of the invention as set forth in the appended claims. 110

I do not restrict myself unessentially, but what I claim and desire to secure by Letters Patent is:—

1. A portable fountain brush comprising a body having a passage therethrough and a valve chamber intersecting said passage at right angles, a barrel mounted in said body and forming an abutment at the outer end of said valve chamber laterally from said passage, a valve mounted in said valve chamber, a stem in connection with said valve extending through said barrel, a shoulder integral with said stem in and of less diameter than said chamber spaced from said valve and limiting outward movement of said stem and valve by abutment against said barrel, a finger button at the outer end of said stem beyond said body in position for natural and convenient engagement by the forefinger of the hand wielding said brush, packing in the inner end of said barrel around

said stem preventing passage of liquid from said valve chamber into said barrel, and a spring encircling said stem in said barrel pressing said packing to position and actuating said stem outwardly. 25

2. In a fountain brush, a body having a passage therethrough and a valve chamber at right angles to and intersecting said passage, a valve stem extending into said valve chamber, a shoulder on said valve stem in said valve chamber spaced from and of less diameter than the diameter of said chamber leaving a space around said shoulder within the valve chamber, an abutment for said shoulder at the outer end of said valve chamber, a valve in said valve chamber spaced from said shoulder and movable by said stem to open said passage, and a spring holding said valve in position to close said passage. 30 35 40
